UNITED STATES PATENT OFFICE.

ALLIE SMITH, OF MINNEAPOLIS, MINNESOTA.

DOOR-KEY RETAINER.

Application filed January 12, 1927. Serial No. 160,586.

This invention relates to key retainers, and has for its main object to provide a simple but highly efficient device adapted to be carried by or attached to an ordinary key, 5 whereby in co-operation with the key hole of a door, said key will be prevented from being surreptitiously removed from the opposite side of the door.

In the ordinary type of door having the 10 key hole extending therethrough, it is a comparatively simple expedient to manipulate and turn an inside key in the lock from the outside of the door by means of a similar key or skeleton key and to force the inside key 15 out of the lock after alining the same with the key hole. My device provides simple means whereby the inside key is prevented from turning in the lock and consequently from removal therefrom.

20 A more specific object of the invention is to provide a wedge member adapted to engage the inside plate of the door about the key hole, said wedge member being connected with the handle portion of the key to prevent oscillation of said key in the lock, simple means being provided for quickly setting the device in working position and withdrawing the same for removal of the key.

These and other objects of the invention 30 will be apparent from the following description made in connection with the accompanying drawing wherein like reference characters refer to similar parts throughout the several views, and in which:

35 Fig. 1 is an elevation of the free edge of a door provided with the usual type of lock and having a preferred embodiment of my invention applied thereto;

Fig. 2 is a plan view of my device carried 40 by a door key; and

Fig. 3 is a vertical section taken on the line 3—3 of Fig. 1.

In the drawings, a portion of a door 4 is 45 illustrated having mounted thereon the usual lock indicated as an entirety by the numeral 5, the latch of which is controlled by the knob 6. The usual door plate 7 in which the knob is journaled is secured to the inner surface of the door being provided with the key 50 hole 8, communicating with the locking mechanism. The skeleton key 9, of usual type is shown having the flat annular handle 9^a.

In Fig. 1 the key 9 is shown inserted in 55 the door lock and turned to substantially

horizontal position, in which withdrawal from the lock is impossible.

I provide a wedge shape or frusto-conical plug 10 carried at one end of a square rod or plunger 11, and rigidly connected thereto. 60 Rod 11 is slidably journaled in a strap or frame 12, which is preferably formed from a flat strip of material, shaped to afford a pair of oppositely disposed ears 12^a having alined square apertures therein to receive 65 rod 11. The strap 12 also includes a resilient hook portion 13 adapted to engage a portion of the key handle 9^a. Strap 12 is preferably made of a strip of material of sufficient width to permit of little turning of 70 said strap relatively to the key handle 9^a when attached thereto.

The strap 12 is secured to the rod 11 in any suitable manner, such as by a coiled or split ring 14 passing through a small transverse 75 hole in the outer end of rod 11, and a coiled compression spring 15 is interposed between the inner ear 12^a of strap 12 and the plug or head 10.

As seen in Fig. 3, the key engaging surface of the plug 10 is preferably concave to 80 substantially conform to the shaft of the key.

In operation, the hook 13 is first secured to the handle 9^a and the key inserted in the door and the door locked. The key is then 85 turned to substantially horizontal position, whereupon the ring 14 may be manipulated to move plug 10 in the direction of strap 12 against the tension of spring 15. The extremity of plug 10 may then be inserted in 90 the circular portion of the key hole in plate 7 above the shaft of the key and the ring 14 released. Compression spring 15 will yieldingly force plug 10 into the key hole, so that it will be practically impossible to move the 95 plug from the opposite side of the door. The connection between strap 12 and the annular handle of the key positively prevents oscillation of the key relatively to the plug 10 and plunger 11.

100 Since it is impossible to exert any substantial amount of leverage on the key from the outer side of the door, my device will render surreptitious entry of the door impracticable.

105 It will be seen that my device is simple in nature, capable of manufacture at exceedingly low cost, and can be carried by the key at all times conveniently as a key ring, which may be easily supported on a hook or nail 110

when the key is not in use. The strap 12 may be quickly attached to the key handle 9^a due to the resilient nature of hook portion 13.

5 It will, of course, be understood that various changes may be made in the form, details, arrangement and proportions of parts without departing from the scope of the invention.

10 What is claimed is:

1. A door key retainer comprising a tapered member adapted to be seated against oscillation in the round part of a key hole against the shaft of a key, a plunger carried 15 by said tapered member and axially alined therewith, a connection member in which said plunger is slidably mounted but held against oscillation, an elastic element interposed between said tapered member and 20 said connection member, a stop disposed adjacent the rear end of said plunger to limit the slidable movement of said plunger in said connection member, said connection member having a substantially flat hook

adapted to pass through the annular handle 25 of a key to hold said key against oscillation in the door lock.

2. A door key retainer comprising a tapered member adapted to be seated against oscillation on the round part of a key hole 30 against the shaft of a key, a plunger of rectangular cross section carried by said tapered member and axially alined therewith, a U-shaped member having oppositely alined rectangular apertures in which said plunger 35 is slidably mounted, a coiled spring surrounding said plunger and interposed between said tapered member and said U-shaped member, a handle disposed adjacent the rear extremity of said plunger adapted to limit the forward movement of said plunger in said U-shaped member, said U-shaped member also carrying a substantially flat resilient hook adapted to pass through the annular handle of a key to retain the same against oscillation.

In testimony whereof I affix my signature.

ALLIE SMITH.
